UNITED STATES PATENT OFFICE.

ARTHUR W. SIMMONS, OF LUFKIN, TEXAS.

DRIVING-BOX.

1,289,562.

Specification of Letters Patent.

Patented Dec. 31, 1918.

Application filed February 16, 1918. Serial No. 217,614.

To all whom it may concern:

Be it known that I, ARTHUR W. SIMMONS, a citizen of the United States, residing at Lufkin, in the county of Angelina and State 5 of Texas, have invented certain new and useful Improvements in Driving-Boxes, of which the following is a specification, reference being had to the accompanying drawings.

10 This invention relates to certain improvements in locomotive driving boxes, and it is an object of the invention to provide a device of this general character simple, efficient and as durable as a solid box greatly 15 reducing the cost of maintaining a locomotive in service by eliminating the necessity of holding it out of service for long periods of time due to driving box trouble by overcoming the difficulties of a solid box, with 20 a hub liner which may be removed or applied to the box with convenience and facility, without the necessity of moving the box from its place on the journal, when it becomes necessary to take up the lateral 25 wear; and which also permits the removal of the box without the necessity of taking the wheels from under the locomotive for renewal of crown brass.

It is also an object of the invention to provide a device of this general character having novel and improved means whereby lubricant may be delivered to various surfaces of the box or brass.

The invention consists in the details of 35 construction and in the combination and arrangement of the several parts of my improved driving box whereby certain important advantages are attained and the device rendered simpler, less expensive and otherwise 40 more convenient and advantageous for use as will be hereinafter more fully set forth.

The novel features of my invention will hereinafter be definitely claimed.

45 In order that my invention may be the better understood, I will now proceed to describe the same with reference to the accompanying drawings, wherein:

Figure 1 is a view in elevation of the hub 50 side of a driving box constructed in accordance with an embodiment of my invention;

Fig. 2 is a view in side elevation with a portion broken away of my driving box as herein embodied;

Fig. 3 is a view in elevation of the hub 55 face of my improved box with the hub liner removed;

Fig. 4 is a sectional view taken substantially on the line 4—4 of Fig. 2;

Fig. 5 is a view partly in elevation and 60 partly in section of my improved box as herein disclosed with the brass and cellar removed but indicated by dotted lines;

Fig. 6 is a cross sectional view taken through my improved box; 65

Fig. 7 is a view in top plan of my box as herein employed; and

Fig. 8 is a view in rear elevation of one of the sections of the flange hub liner as herein embodied. 70

While my invention is primarily intended for use as a driving box for locomotives, it is to be understood that it may also be employed for use as a trailer and truck box. As herein disclosed my improved box comprises an arch 1 and the walls or side members 2. The upper portion of the walls or side members 2 are provided with the transversely disposed dove-tailed grooves 5 to receive the corresponding side flanges 6 carried by the cellar 7, provided this flange fit on cellar is desired, if not, the flange may be left off thereby producing what would be termed a straight fit. The cellar 7 is positioned between the walls or side members 2 80 in a conventional manner and is maintained in applied position through the medium of the cellar pins 8 or the like. The central portion of the arch 1 at its upper portion and at the hub side of the box is provided with the outstanding block 9 having its bottom face undercut or inwardly beveled as at 10 for a purpose which will hereinafter be more particularly referred to. 85

The hub face of the arch 1 and the corresponding faces of the walls or side members 2 are provided with the transversely disposed dove-tailed grooves 11 adapted to slidably receive correspondingly formed flanges 12 carried by the rear or inner faces 100 of the sections 14 of the flanged hub liner. The inner ends of the flanges 12 have the

corners 15 thereof rounded in order to facilitate the insertion of the flanges 12 within the grooves 11.

The sections 14 are substantially in duplicate and the outer side marginal portions of each of said sections are provided with the inwardly directed flange 16 extending from the upper end thereof and terminating as at 17 at a predetermined distance below the lower end thereof. The flanges 16 contact with the outer faces of the walls or side members 2 so that the inward sliding movement of the sections 14 relative to the hub face of the box is limited. The flanges 16 also coat with the pedestal of the frame in a conventional manner. The outer face of the flange 16 is provided with the hand grasps 18 to afford means whereby the requisite sliding movement may be imparted to the sections 14 as the occasion of practice may require. The upper marginal portion of the section 14 at its inner end is provided with an upstanding extension 19 having its top surface 20 beveled to correspond with the beveled bottom face 10 of the block 9 so that said extension 19 snugly engages beneath said block. The bottom face 10 of the block 9 and the upper face 20 of the extension 19 are provided with the registering grooves 21 affording a bore or passage-way in which is snugly fitted the pin 22. The pin 22 is of such a length as to coat with the extensions 19 of both of the sections 14 and to extend beyond the outer ends of said extensions 19. Engaged with the extended portions of the pin 22 are the clamping nuts 23 of a conventional type. By this arrangement an effective anchoring means is afforded for the upper portions of the sections 19.

The inner vertical margins of the outer face of the walls or side members 2 of the box are also provided with the outstanding solid flanges 24 which are adapted to coat with the pedestal in a conventional manner and the opposed face 25 of the flanges 16 and 24 are longitudinally curved or rounded so that in practice the box is capable of limited lateral movement, and it is also to be understood that the face 25 of flange 16 should be rounded more than the face 25 of the flange 24 thereby relieving flange 16 of the strain. This lateral movement serves to compensate for the vertical movement of the driving wheel occasioned by a low or high joint in a track. This rocking or lateral movement of the box materially relieves the top and bottom portions of the flanges from the strain occasioned by such high and low joints in the track.

The walls or side members of the box at the hub face are provided with depending lugs 26 adapted to aline with the depending

portions 17 of the sections 14 and coating with said depending portions 17 and lugs 26 are the clamping or holding bolts 27 which serve as additional means for maintaining the sections of the hub or liner plate in applied or assembled position. As is particularly illustrated in Fig. 1, it is to be noted that the clamping bolts 27 are so arranged as to afford no obstruction to the removal or application of the cellar 7.

It is also to be noted as particularly illustrated in Fig. 2 that the cellar pins 8 extend through the flanges 16 of the sections 14 of the hub liner. It is also preferred that the marginal portions of each of the sections 14 at opposite sides of the flanges 12 and the adjacent portion of the flange 16 be cut out or recessed as at 28 so that the inner face of the sections 14 may be properly machined. It is also desired that the flanges 24 be provided with the depending extensions or lugs 29 with which a suitable rod or the like (not shown) may be engaged to help prevent the walls or side members from slightly springing should it ever occur.

The upper face of the arch 1 at substantially the transverse center thereof is provided with the pockets 30 to receive a locomotive spring saddle as is now generally employed.

The upper face of the arch 1 is also provided with the pockets 31 extending transversely of the walls or side members 2 of the box and the side pockets have the central portions of their outer longitudinal faces open while the intermediate or central pocket is separated from said outer pockets by the flanges 32. Each of the outer faces of the walls or side members 2 is provided with the lubricating grooves 33 in communication with an outer pocket 31 adjacent the opposite ends of the central open portion of the outer face or wall thereof.

In communication with the end portions of the outer pockets 31 adjacent the hub or flange liner are the channels or openings 34 which extend downwardly and outwardly on a predetermined incline and which are also continued through the sections 14 of the hub or flange liner whereby the outer faces of the sections 14 may be lubricated. The intermediate pocket or recess 31 is provided with the downwardly directed openings or passage ways 35 which are adapted to be continued by suitable openings in the crown brass 4 so that the contacting face of the crown brass may be suitably lubricated. Extending transversely of the pockets or recesses 31 at substantially the longitudinal center thereof is a heating member or pipe 36 which has in communication with its central portion a flexible pipe 37 leading from a supply pipe 38 in communication with a

suitable source of steam or other heating medium. It is also to be understood that the heating member or pipe 36 is to have a small opening or drain pipe at each end thereof provided steam is used.

In practice the pockets or recesses 31 are filled with a suitable lubricating grease. The lubricant will travel through the several openings or recesses 34 and 35 and 10 grooves 33 to effect the desired lubrication.

Arranged within each of the outer recesses or compartments 31 is a follower strip 39 extending longitudinally thereof and which is constantly urged toward the outer faces of 15 the walls or side members 2 by the expandable members 40 herein disclosed as coil springs interposed between the follower 39 and a flange 32. The outer wall of each of the side recesses or compartments 31 adjacent the 20 hub face of the box is provided with an inwardly disposed bevel 41 whereby a supplemental pocket is afforded to assure the desired flow of lubricant through an opening or passageway 34.

From the foregoing description it is thought to be obvious that a driving box constructed in accordance with my invention is particularly well adapted for use by reason of the convenience and facility with which it 30 may be assembled and operated and it will also be obvious that my invention is susceptible of some change and modification without departing from the principles and spirit thereof and for this reason I do not wish to 35 be understood as limiting myself to the precise arrangement and formation of the several parts herein shown in carrying out my invention in practice except as hereinafter claimed.

40 I claim:

1. In combination with a driving box including an arch and side members and having transversely disposed grooves in the hub face thereof, a hub plate embodying duplicate sections, transversely disposed ribs carried by the inner face of said sections and slidably engaged within the grooves of the box, and an outstanding block carried by the 45 hub face of the arch of the box, the bottom face of said block being inwardly beveled, each of the sections of the hub plate being provided with upwardly directed extensions, the top face of each extension being beveled to engage the beveled bottom face of the 50 block.

2. In combination with a driving box including an arch and side members and having transversely disposed grooves in the hub face thereof, a hub plate embodying duplicate sections, transversely disposed ribs carried by the inner face of said sections and slidably engaged within the grooves of the box, an outstanding block carried by the 55 hub face of the arch of the box, the bottom

face of said block being inwardly beveled, 65 each of the sections of the hub plate being provided with upwardly directed extensions, the top face of each extension being beveled to engage the beveled bottom face of the block, the opposed faces of the block and extension being provided with registering recesses, and a pin seatable within said registering recesses, and clamping means carried by the extremities thereof and engageable with the ends of the block. 70 75

3. A hub box comprising an arch and side members, the opposed vertical margins of each of the side members being provided with outstanding flanges, the opposed faces of the flanges being longitudinally rounded 80 to permit lateral movement of the box when in applied position.

4. A driving box including an arch and side members, the top face of the arch being provided with recesses to receive lubricant, 85 the outer faces of the side members being provided with grooves in communication with certain of said recesses, and followers arranged within the recesses with which the 90 grooves communicate.

5. A driving box including an arch and side members, the top face of the arch being provided with recesses to receive lubricant, the outer faces of the side members being provided with grooves in communication 95 with certain of said recesses, followers arranged within the recesses with which the grooves communicate, and openings in communication with said last named recesses and discharging upon the hub face of the 100 box.

6. In combination with a driving box including an arch and side members and having transversely disposed grooves in the hub face thereof, a hub plate embodying duplicate sections, transversely disposed ribs carried by the inner face of said sections and slidably engaged within the grooves of the box, and means coacting with the inner end portions of the upper edges of the sections 110 for holding the upper portions of the sections in applied position.

7. A driving box including an arch and side members, the top face of the arch being provided with recesses to receive lubricant, 115 lubricant conducting conduits in communication with the recesses, and a heating medium extending within the recesses.

8. A driving box including an arch and side members, the top face of the arch being 120 provided with recesses to receive lubricant, lubricant conducting conduits in communication with the recesses, a hollow member intersecting the recesses, and means for delivering heat within said hollow member. 125

9. In combination with a driving box, a hub plate embodying substantially duplicate sections, each of said sections having slid-

4
able engagement with the hub face of the driving box, and means coacting with adjacent portions of the sections for holding the same in applied position.

5 10. In combination with a driving box, a hub plate embodying substantially duplicate sections, each of said sections having slideable engagement with the hub face of the driving box, and means common to both of

the sections for holding the same in applied 10 position.

In testimony whereof I hereunto affix my signature in the presence of two witnesses.

ARTHUR W. SIMMONS.
